REFERENCE VOLTAGE CIRCUIT
INCLUDING TRANSISTOR

BACKGROUND OF THE INVENTION

1. Field of the Invention

The present invention relates to a reference voltage circuit using bipolar transistors.

2. Description of the Related Art

Conventionally, a reference voltage circuit (referred to as the bandgap reference voltage circuit) obtains a temperature-compensated bandgap reference voltage by using a bandgap voltage of a bipolar transistor is known.

The reference voltage circuit generates a reference voltage of which temperature dependence is suppressed by causing the positive temperature dependence and the negative temperature dependence generated by two circuit blocks to offset each other.

Here, there is a requirement to reduce the number of bipolar transistors as much as possible for semiconductors that use transistors such as MOSFETs. In addition, there is a requirement to reduce the influence of noise from an output end of the reference voltage.

SUMMARY OF THE INVENTION

A reference voltage circuit according to the present invention includes:

- a first current source, through which a first current is made to flow;
  - a second current source, through which a second current is set at a certain ratio to the first current is made to flow;
  - a first current path, which includes a second resistor, a first resistor, and a first bipolar transistor that are connected to the first current source in a sequential manner, and through which the first current is made to flow;
  - a second current path, which includes a third resistor and a 0th bipolar transistor that are connected to the second current source in sequential manner, and through which the second current is made to flow;
  - an operational amplifier, which controls current amounts of the first current and the second current by an output from an output end, and of which a positive input end is connected to a connection point between the second resistor and the first resistor, and of which a negative input end is connected to a connection point between the third resistor and the 0th bipolar transistor; and
  - a buffer amplifier, which outputs a reference voltage, and of which a positive input end is connected to a connection point between the second current source and the third resistor, and a negative input end of which is connected to an output end; wherein
- an area ratio of the first bipolar transistor to the 0th bipolar transistor is $n:1$, and
- a reference voltage of which temperature dependence is corrected is obtained by adjusting resistance values of the first and the third resistor and a value of the area ratio n .

According to the reference voltage circuit of the present invention, by adjusting resistance values of the third resistor and the first resistor $R1$ and the area ratio n of the two bipolar transistors, a reference voltage of which temperature depen-

2

dence is suppressed can be obtained, and the intrusion of noise from the output end can be suppressed by the buffer amplifier.

5 BRIEF DESCRIPTION OF THE DRAWINGS

FIG. 1 is a circuit diagram showing an example of a reference voltage circuit (bandgap reference voltage circuit) according to an embodiment of the present invention.

10 FIG. 2 is a circuit diagram showing another example of the reference voltage circuit according to the embodiment of the present invention.

15 FIG. 3 is a diagram showing temperature characteristics of currents $iptat$, $iztc$, and $im5$ and a reference voltage $vref$.

PREFERRED EMBODIMENT OF THE PRESENT
INVENTION

20 Hereinafter, embodiments of the present invention are described with reference to the drawings. It should be noted that the following embodiments are not intended to limit the scope of the present invention, and configurations formed by selectively combining multiple examples are also included in the present invention.

[Circuit Configuration]

25 FIG. 1 is a circuit diagram showing an example of a reference voltage circuit according to an embodiment of the present invention. The reference voltage circuit is disposed in a semiconductor integrated circuit that uses a complementary MOS (CMOS) gate, for example.

30 A power supply vdd supplies a predetermined positive voltage (for example, 5 V). A first current path $CP1$ and a second current path $CP2$ are connected to the power supply vdd . The other ends of the first current path $CP1$ and the second current path $CP2$ are connected to ground agnd.

35 The first current path $CP1$ includes a first transistor $M1$, a second resistor $R2$ (referred to as the "resistor $R2$ " hereinafter), a first resistor $R1$ (referred to as the "resistor $R1$ " hereinafter), and a first bipolar transistor $Q1$ that are connected in series from the power supply vdd toward the ground agnd in a sequential manner.

40 The first transistor $M1$ is a p-channel metal oxide semiconductor field effect transistor (MOSFET), and the source of the first transistor $M1$ is connected to the power supply vdd . Note that the first transistor $M1$ functions as a first current source. The resistor $R1$ and the resistor $R2$ are connected in series to the drain of the first transistor $M1$. The first bipolar transistor $Q1$ connected to the other end of the resistor $R2$ is an npn-type bipolar transistor. To note on the first bipolar transistor $Q1$, there is a short between the base and the collector, the source is connected to the resistor $R2$, and the emitter is connected to the ground agnd.

45 The second current path $CP2$ includes a second transistor $M2$, a third resistor $R3$ (referred to as the "resistor $R3$ " hereinafter), and a 0th bipolar transistor $Q0$ that are connected in series from the power supply vdd toward the ground agnd in a sequential manner. The second transistor $M2$ is a p-channel metal oxide semiconductor field effect transistor (MOSFET), and the source of the second transistor $M2$ is connected to the power supply vdd .

50 Note that the second transistor $M2$ functions as a second current source. The resistor $R3$ is connected to the drain of the second transistor $M2$. The 0th bipolar transistor $Q0$ connected to the other end of the resistor $R3$ is an npn-type bipolar transistor. To note on the 0th bipolar transistor $Q0$, there is a short (diode connection) between the base and the

collector, the source of which is connected to the resistor R_3 , and the emitter of which is connected to the ground agnd.

A connection point between the resistor R_2 and the resistor R_1 of the first current path CP_1 is connected to the positive input end of an operational amplifier A_1 . In addition, a connection point between the second transistor M_2 and the resistor R_3 of the second current path CP_2 is connected to the negative input end of the operational amplifier A_1 . Besides, gates of the first transistor M_1 and the second transistor M_2 are commonly connected to the output end of the operational amplifier A_1 .

An area (emitter area) ratio of the first bipolar transistor Q_1 to the 0th bipolar transistor Q_0 is $n:1$, and when a reverse saturation current of the 0th bipolar transistor Q_0 is set as i_{s0} , then a reverse saturation current i_{s1} of the first bipolar transistor Q_1 equals n^*i_{s0} . In addition, in this example, the current iM_1 made to flow by the first transistor M_1 and the second transistor M_2 and the current iM_2 made to flow by the second transistor M_2 are the same, that is, $iM_1=iM_2$. Note that iM_1 and iM_2 can still be used even if iM_1 and iM_2 are not the same, as long as iM_1 and iM_2 are at a constant ratio.

Moreover, in this example, there is a third transistor M_3 of which the gate is commonly connected to the gates of the first transistor M_1 and the second transistor M_2 . The third transistor M_3 is also a p-channel MOSFET, the source of the third transistor M_3 is connected to the power supply vdd , and a current which is made to flow by the third transistor M_3 is the same as the currents which are made to flow by the first transistor M_1 and the second transistor M_2 . Note that the current flowing through the third transistor M_3 is referred to as "iptat". The current iptat of the third transistor M_3 can be monitored.

Furthermore, the connection point between the resistor R_3 and the second transistor M_2 is connected to the positive input end of a buffer amplifier A_2 , and a reference voltage $Vref$ is output from the output end of the buffer amplifier A_2 . Note that there is a short circuit between the negative input end and the output end of the buffer amplifier A_2 .

Next, operations of the circuit shown in FIG. 1 are described.

<Setting Conditions>

The first transistor M_1 and the second transistor M_2 are transistors having the same characteristics ($M_1=M_2$). Therefore, the currents of the first transistor M_1 and the second transistor M_2 are set to be the same ($iM_1=iM_2$). Alternatively, the currents of the first transistor M_1 and the second transistor M_2 may be set in an arbitrary ratio, and the magnitude of an error signal between the two current paths can be adjusted. Moreover, in the design, it is advisable to adjust the respective resistance values to values inversely proportional to values of the flowing currents in order that voltages generated by the respective resistors do not change. In addition, the area (emitter area) ratio of the first bipolar transistor Q_1 to the 0th bipolar transistor Q_0 is $n:1$ ($Q_1:Q_0=n:1$). Here, n may be a positive integer, or may not be an integer.

The base-emitter voltage of the first bipolar transistor Q_1 is set as VBE_1 , the base-emitter voltage of the 0th bipolar transistor Q_0 is set as VBE_0 , the voltage of the connection point between the first transistor M_1 and the resistor R_2 is set as Vbg_1 , and the voltage of the connection point between the second transistor M_2 and the resistor R_3 is set as Vbg_0 . Lastly, resistance values of the resistors R_1 , R_2 , and R_3 are set as R_1 , R_2 , and R_3 , respectively.

<Operation>

The voltage of the positive input end of the operational amplifier A_1 is to $VBE_1+R_1^*M_1$, and the voltage of the negative input end is VBE_0 .

Thus, the operational amplifier A_1 controls the gates of M_1 and M_2 so that $VBE_1+R_1^*M_1=VBE_0$, and the amounts of the currents iM_1 and iM_2 are determined.

In addition, the base-emitter voltage VBE_0 of the 0th bipolar transistor Q_0 is

$$VBE_0=vt^*\ln(iM_2/is_0),$$

and the base-emitter voltage VBE_1 of the first bipolar transistor Q_1 is

$$VBE_1=vt^*\ln(iM_1/n^*is_0).$$

Here, $vt=kT/Q$, and is_0 denotes the reverse saturation voltage of the 0th bipolar transistor Q_0 as described above. In addition, k denotes the Boltzmann constant, T denotes absolute temperature, and Q denotes elementary charge.

Thus,

$$R_1^*M_1=VBE_0-VBE_1=vt^*\ln(iM_2/is_0)-vt^*\ln\{iM_1/(n^*is_0)\}=vt^*\ln(iM_2^*n/iM_1),$$

and since $iM_1=iM_2$ and $vt=kT/Q$,

$$iM_1=[k^*\ln(n)/(Q^*R_1)]^*T.$$

In addition, the current which is made to flow by the third transistor M_3 is the same as iM_1 , and $iM_1=iptat$.

Here, approximation is performed by $VBE_0=Eg/Q-mT$. A representative value of m is 2.2 mV/K, and Eg denotes bandgap. For Si, $Eg=1.21$ eV (representative value: the 0 K intersection point in the first-order approximation), and an actual value at 0 K is 1.165 eV.

And, the two-end voltage Vr_3 of the resistor R_3 is

$$Vr_3=iM_1^*R_3=[k^*\ln(n)/(Q^*R_1)]^*R_3^*T.$$

Here, $Vbg_0=VBE_0+Vr_3$, and when the temperature coefficient in of VBE_0 and the temperature coefficient $[k^*\ln(n)/(Q^*R_1)]^*R_3$ of Vr_3 are equal, m does not change due to the temperature T .

Thus, by adjusting the values of n , R_1 , and R_3 of $m=[k^*\ln(n)/(Q^*R_1)]^*R_3$, Vbg_0 can be set to be independent of temperature.

Furthermore, by causing R_2 to equal to R_3 , source-drain voltages (Vds) of the first transistor M_1 and the second transistor M_2 become equal, then the error between M_1 and M_2 becomes smaller.

In addition, in the embodiment, the voltage vbg_0 is not directly output, but is output via the buffer amplifier A_2 . Thus, the buffer amplifier A_2 suppresses the intrusion of noise from the output destination. Thereby, the reference voltage $Vref$ can be made stable.

In this way, according to the circuit shown in FIG. 1, by using two bipolar transistors, namely the first bipolar transistor Q_1 and the 0th bipolar transistor Q_0 to adjust the resistors R_3 and R_1 and the area ratio n of the two bipolar transistors, the reference voltage $Vref$ of which temperature dependence is suppressed can be obtained.

[Other Circuit Configurations]

FIG. 2 is a circuit diagram showing another example of the reference voltage circuit according to the embodiment of the present invention.

With regard to the reference voltage in the reference voltage circuit shown in FIG. 1, linear temperature dependence can be eliminated. However, it is known that the reference voltage obtained in this way has a negative secondary temperature characteristic. Therefore, n , R_1 , and R_3 are adjusted to eliminate temperature dependence up to a predetermined temperature T_1 , and thus at or above the

predetermined temperature T_1 , the reference voltage decreases in response to an increase in temperature.

In the reference voltage circuit shown in FIG. 2, a drop in the reference voltage at or above the predetermined temperature T_1 is compensated by generating a correction voltage.

In this circuit, a correction resistor R_4 is disposed between the emitters of both the first bipolar transistor Q_1 and the 0th bipolar transistor Q_0 and the ground agnd. Thus, emitter voltages of both the first bipolar transistor Q_1 and the 0th bipolar transistor Q_0 increase due to the current flowing through the correction resistor R_4 .

In addition, a fourth transistor M_4 is connected to the power supply vdd . The fourth transistor M_4 is a p-channel FET similar to the first transistor M_1 and the second transistor M_2 , the gate of the fourth transistor M_4 is commonly connected to the gates of the first transistor M_1 and the second transistor M_2 , and the source of the fourth transistor M_4 is connected to the power supply vdd .

The source of a fifth transistor M_5 is connected to the drain of the fourth transistor M_4 , and the drain of the fifth transistor M_5 is connected to a connection point between the correction resistor R_4 and the emitters of the first bipolar transistor Q_1 and the 0th bipolar transistor Q_0 . A voltage V_g which turns on the fifth transistor M_5 is supplied to the gate of the fifth transistor M_5 .

The drain of a sixth transistor M_6 which is an n-channel FET is connected to a connection point between the fourth transistor M_4 and the fifth transistor M_5 . The source of the sixth transistor M_6 is connected to the ground aged via a resistor R_5 .

In addition, an operational amplifier A_3 , in which the voltage V_{bg0} is input to the positive input end, is arranged. The output end of the operational amplifier A_3 is connected to the gate of the sixth transistor M_6 , and the negative input end of the operational amplifier A_3 is connected to the source of the sixth transistor M_6 .

Thus, the operational amplifier A_3 operates so that the source of the sixth transistor M_6 becomes V_{bg0} . Here, the source voltage of the sixth transistor M_6 is determined by the current flowing through the resistor R_5 , and thus the sixth current izc flowing through the sixth transistor M_6 equals V_{bg0}/R_5 , and the sixth current izc constantly flows through the sixth transistor M_6 . Note that the sixth current izc corresponds to the voltage V_{bg0} and is referred to as zero temperature coefficient current.

In this circuit, the current $iptat$ attempts to be made to flow by the fourth transistor M_4 in the same way as the third transistor M_3 , but in a case that the current izc is greater than the current $iptat$, the current izc is made to flow by the fourth transistor M_4 . That is, the greater current of the current izc and the current $iptat$ is made to flow through the fourth transistor M_4 . The current is referred to as the fourth current.

The sixth transistor M_6 , through which the current izc is made to flow is connected to the drain of the fourth transistor M_4 . Thus, when the current $iptat$ flows through the fourth transistor M_4 , the current $im5$ flowing through the fifth transistor M_5 equals $iptat - izc$. In addition, when the current izc flows through the fourth transistor M_4 , the current $im5$ flowing through the fifth transistor M_5 equals 0.

The current $im5$ flowing through the fifth transistor M_5 flows through the correction resistor R_4 as a correction current. Thus, each of the emitter voltages of the first bipolar transistor Q_1 and the 0th bipolar transistor Q_0 increases by $im5 \cdot R_4$, which serves as a correction voltage and is also added to the reference voltage $Vref$.

FIG. 3 is a diagram showing temperature characteristics of currents $iptat$, izc , and $im5$ and the reference voltage $Vref$.

The reference voltage circuit shown in FIG. 1 is configured to have the best temperature characteristic at or below the predetermined temperature T_1 . Thus, at temperatures higher than the predetermined temperature T_1 , as shown by a dotted line in FIG. 3, the reference voltage $Vref$ drops as the temperature rises due to the negative secondary temperature characteristic.

The current $iptat$ is the same as the current $iM1$, and is expressed as $[k^* \ln(n)/(Q^* R1)]^* T$, which linearly increases as temperature rises. On the other hand, the current izc is a current corresponding to the temperature coefficient at the temperature 0 K and is constant even if the temperature changes, and in the embodiment, the current $iptat$ and the current izc intersect at the predetermined temperature T_1 .

When the temperature T is lower than the predetermined temperature T_1 , $iptat$ is less than izc , and thus the fifth transistor M_5 turns off and all of the current $iptat$ flows through the sixth transistor M_6 . On the other hand, when the temperature T is higher than the predetermined temperature T_1 , $iptat$ is greater than izc , and the correction current $im5$ which equals $iptat - izc$ is generated. The correction current $im5$ is generated through subtracting a constant izc from the linearly increasing $iptat$, and linearly increases as the temperature rises.

By making the correction current $im5$ to flow in the resistor R_4 , a voltage of $im5 \cdot R_4$ is generated in the resistor R_4 , which serves as a correction voltage of the reference voltage $Vref$.

Here, the voltages $vbg0$ and $vbg1$ increases by an amount corresponding to the amount of current flowing through the correction resistor R_4 , but even in the case that the correction current $im5$ equals 0, currents from the first current path $CP1$ and the second current path $CP2$ flow through the correction resistor R_4 .

When the correction current $im5$ equals 0, the voltage $Vr4$ of the correction resistor R_4 is

$$Vr4 = (iM1 + iM2) \cdot R4 = 2 \cdot iM1 \cdot R4$$

Therefore, in the circuit shown in FIG. 2, the resistors R_2 and R_3 may be reduced by an amount that matches with the voltage $Vr4$ as compared with that in the circuit shown in FIG. 1.

In this case, with regard to the reduction amount $r2$ of the resistors R_2 and R_3 ,

$$r2 \cdot iM1 = 2 \cdot iM1 \cdot R4,$$

$$\text{thus, } r2 = 2 \cdot R4.$$

In addition, in view of the correction current $im5$, $r2$ may be set greater than $2 \cdot R4$.

Furthermore, the correction based on the correction current $im5$ assumes that the correction is up to a predetermined temperature T_2 higher than the predetermined temperature. Thus, at even higher temperatures, $Vref$ drops due to the negative secondary characteristic. Therefore, a highly-precise $Vref$ can be generated by adding a plurality of correction circuits that are the same as the correction circuit described above and generate correction currents at or above temperatures T_3 and T_4 that are higher than the predetermined temperature T_2 .

What is claimed is:

1. A reference voltage circuit, comprising:
a first current source, through which a first current is made to flow;

a second current source, through which a second current set at a certain ratio to the first current is made to flow; a first current path, which comprises a second resistor, a first resistor, and a first bipolar transistor that are connected to the first current source in a sequential manner, and through which the first current is made to flow;

a second current path, which comprises a third resistor and a 0th bipolar transistor that are connected to the second current source in a sequential manner, and through which the second current is made to flow;

an operational amplifier, which controls current amounts of the first current and the second current by an output from an output end, and of which a positive input end is connected to a connection point between the second resistor and the first resistor, and of which a negative input end is connected to a connection point between the third resistor and the 0th bipolar transistor; and

a buffer amplifier, which outputs a reference voltage, and of which a positive input end is connected to a connection point between the second current source and the third resistor, and of which a negative input end is connected to an output end; wherein

an area ratio of the first bipolar transistor to the 0th bipolar transistor is n:1, and

a reference voltage of which temperature dependence is corrected is obtained by adjusting resistance values of the first and the third resistor and a value of the area ratio n.

2. The reference voltage circuit according to claim 1, wherein

the first current source comprises a first transistor through which the first current is made to flow;

the second current source comprises a second transistor through which the second current is made to flow, gates of the first transistor and the second transistor are commonly connected,

the output end of the operational amplifier is connected to the gates of the first transistor and the second transistor, and

the first current and the second current are the same.

3. The reference voltage circuit according to claim 2, wherein

the second resistor is disposed between the first transistor and the first resistor of the first current path, and resistance values of the second resistor and the third resistor are the same.

4. The reference voltage circuit according to claim 2 or 3, wherein

in a case that temperature coefficients of base-emitter voltages of the first bipolar transistor and the 0th bipolar transistor are set as m, a resistance value of the first resistor is set as R1, a resistance value of the third resistor is set as R3, k represents the Boltzmann constant, and Q represents elementary charge, values of n, R1, and R3 are adjusted so that

$$m = [k * \ln(n) / (Q * R1)] * R3.$$

5. The reference voltage circuit according to claim 2, comprising:

a sixth transistor, through which a sixth current corresponding to the reference voltage is made to flow;

a fourth transistor, through which a fourth current is made to flow, the fourth current corresponding to the greater current of a current corresponding to a current flowing through the first transistor or the second transistor and the sixth current;

a fifth transistor, through which a correction current obtained by subtracting the sixth current from the fourth current is made to flow; and

a correction resistor, which is disposed between both the first current path and the second current path and ground, and through which the correction current is made to flow in addition to currents flowing through the first current path and the second current path; wherein temperature dependence of the reference voltage is further corrected.

6. The reference voltage circuit according to claim 5, wherein

at a temperature higher than a predetermined temperature T1, the sixth current exceeds the fourth current.
